UNITED STATES PATENT OFFICE.

FRANK M. BLAIR, OF NEWARK, OHIO, ASSIGNOR TO THE CREE-BECKER OIL TOOL COMPANY, OF NEWARK, OHIO.

CASING ELEVATOR.

Application filed March 30, 1922. Serial No. 543,058.

To all whom it may concern:

Be it known that I, FRANK M. BLAIR, a citizen of the United States, residing at Newark, in the county of Licking and State 5 of Ohio, have invented a new and useful Casing Elevator, of which the following is a specification.

This invention relates to casing elevators designed for raising and lowering casings 10 and tubings of oil, gas, artesian and other wells.

As is well known to those skilled in the art the links constitute the weakest part of casing elevators. When a link has broken, 15 heretofore, it has not been practical to have the same repaired in the field because it is impossible for a blacksmith or anyone not having the necessary equipment, to reproduce the exact compound curvature necessary in links 20 of this character in order to allow the elevator to properly shift the casing without bending, straining or breaking it when the casing or tube to which the elevator is applied is raised or lowered. Because of this 25 fact it has been necessary, in many instances, to substitute an entirely new elevator when one of the links has become broken or, in lieu thereof, to ship the entire elevator to the factory to have a new link supplied.

30 One of the objects of the present invention is to so connect the links to the elevator that new ones can be easily substituted in the field without requiring the services of a skilled mechanic and without requiring the 35 use of special fastening means for holding the links in place, thereby enabling the user to avoid the objections resulting from efforts to repair or replace parts in the field and also to eliminate the expense necessary in 40 order to ship entire elevators to and from a factory for repair.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the 45 invention shown can be made without departing from the spirit of the invention.

In the accompanying drawings the preferred form of the invention has been shown.

In said drawings—
55 Figure 1 is a side elevation of an elevator

having the present improvements combined therewith.

Figure 2 is an elevation of the elevator and showing, in full lines, one of the links while being inserted into engagement with 60 the elevator and, in dotted lines, the position of the link after being assembled with the elevator.

Referring to the figures by characters of reference 1 designates an elevator of the 65 usual two part construction, or some other type the members of the elevator being hingedly connected at one end, as indicated at 2 and being detachably connected at their other end by a latch 3 as shown or in any 70 other manner desired. Lugs 4 are provided at the hinge and latch ends or in other types somewhere in the ear of one of the members, each of these lugs being provided with a slot 5 extending upwardly thereinto from 75 the lower end of the lug and opening into a circular opening 6.

A pair of links are used in connection with the elevator, the two links being duplicates and oppositely disposed as shown 80 in Figure 1. Each link, which has been indicated at 7, has parallel cylindrical portions 8 passing at one end into an end portion 9 which is also circular in cross section while the other ends of the portions 8 gradually diverge toward the other end of the link, as shown at 10, the said link being gradually reduced in thickness from the portions 8 to the end 11 of the link and the width of said end being greater than that 90 of the remainder of the link. The link is also bowed or curved from the portions 8 to the end 11 as shown particularly in Figure 1.

The two links are so proportioned that 95 when they are in their normal positions relative to the elevator the end portions 9 thereof will fit within the openings 6 as shown in Figure 1 while the portions 10 of the links will converge upwardly toward 100 each other and contact as shown at 12. Thus the links can be engaged as ordinarily and the elevator raised and lowered for the purpose of raising or lowering a well casing or tube and as the openings 6 are arranged 105 adjacent the bottom of the elevator and a large amount of metal is located above each of the openings, the provision of these openings in no way weakens the elevator. The device is to be used in the same manner as 110

ordinary elevators of this character and should one of the links become broken the same can be easily removed and another substituted. This substitution is effected by placing a link 7 below the elevator in a position the reverse of that illustrated in Figure 1. The flattened end 11 of the link is inserted upwardly into the slot 5 and opening 6 and the link is then slid longitudinally until said end portion 11 passes out of the opening as shown for example by full lines in Figure 2 and one of the portions 10, and, subsequently, one of the portions 8 come into the opening 6 after which the end portion 9 arrives within the opening. The link after being thus brought to position with the end 9 in the opening 6 and the balance of the link hanging downwardly therefrom, is swung upwardly through 180° until it comes to its raised position as shown by full lines in Figure 1 whereupon the parts will be held properly assembled and cannot be separated except by breaking them or by reversing the movement of the link hereinbefore described.

Obviously by providing a structure such as described it becomes unnecessary to employ any special fastening means for holding the links detachably in place. Furthermore a new link can easily be placed in position without requiring the services of a skilled mechanic.

What is claimed is:

1. The combination with an elevator hav-

ing oppositely extending lugs, there being transverse openings in the lower portions of the lugs and slots extending upwardly to said openings from the lower ends of the lugs, of links of variable thickness removably seated in the openings.

2. The combination with an elevator having oppositely extending lugs, there being an opening in each lug and a slot extending to said opening from the lower end of the lug, of a pair of links detachably seated within the openings, each of said links having its lower end portion normally seated in one of the openings and of greater diameter than the slot leading to the opening.

3. The combination with an elevator having oppositely extending lugs, there being a transverse opening in each lug and a slot extending to each opening from the lower end of the lug, of oppositely disposed links removably mounted within the respective openings, each of said links having its lower end normally seated in one of the openings and of a diameter greater than the width of the slot leading to said opening, each link having a portion thereof of a thickness less than the width of the slot.

In testimony that I claim the foregoing as my own, I have hereto affixed my signature in the presence of two witnesses.

FRANK M. BLAIR.
